UNITED STATES PATENT OFFICE.

MILFORD G. CHANDLER, OF CHICAGO, ILLINOIS.

FLUID-DISTRIBUTING MECHANISM.

1,121,976.

Specification of Letters Patent.

Patented Dec. 22, 1914.

Application filed July 10, 1913. Serial No. 778,380.

To all whom it may concern:

Be it known that I, MILFORD G. CHANDLER, a citizen of the United States, residing at Chicago, in the county of Cook and State of Illinois, have invented a new and useful Improvement in Fluid-Distributing Mechanism, of which the following is a specification.

My invention relates, more particularly, to mechanism for distributing oil to bearings to be lubricated or fluid-fuel to the cylinders of an engine; and my objects, generally stated, are to provide improvements in the above-referred to variety of mechanism, and more especially that of the plunger type, whereby its construction will be simplified and rendered more economical of manufacture; its operation rendered positive; provision will be made for quickly regulating the supply of fluid, operated on, to all points of delivery; uniform flow of fluid to all leads will be effected; and whereby the amount of fluid distributed by the mechanism will be automatically governed by the speed of the engine supplied with the fluid.

Referring to the accompanying drawings, wherein I have shown my invention as embodied in a mechanism for distributing oil through two leads to bearings or other parts of an engine to be lubricated Figure 1 is a view in side elevation of my improved distributing means, a portion thereof being shown in section, the section being taken at the line 1 on Fig. 2 and viewed in the direction of the arrow. Fig. 2 is a section taken at the line 2 on Fig. 1 and viewed in the direction of the arrow, the valve-proper being shown in elevation. Fig. 3 is a view like Fig. 2 in complete sectional elevation. Fig. 4 is a section taken at the line 4 on Fig. 1 and viewed in the direction of the arrow. Fig. 5 is a view diagrammatic in character, showing the connection of my improved distributing means with the throttle-control of an internal-combustion engine for automatically controlling the amount of oil supplied to the parts to be lubricated. Fig. 6 is a broken sectional view taken at the line 6 on Fig. 4 and viewed in the direction of the arrow, this view showing the relative positions occupied by the fluid-forcing plunger, the operating means for the latter and the inlet passages of the valve-proper, when the parts of the distributor are in one position. Fig. 7 is a section taken at the line 7 on

Fig. 4 and viewed in the direction of the arrow, the section being taken through the outlet-port of the valve-proper and showing the position occupied by the latter when the several parts illustrated in Fig. 6 are in the position therein shown. Fig. 8 is a view like Fig. 6 showing the positions assumed by the parts when the plunger-driving eccentric has made a quarter turn from the position illustrated in Fig. 6. Fig. 9 is a view like Fig. 7 showing the position occupied by the outlet-port of the valve-proper when the parts of the mechanism are in the position illustrated in Fig. 8. Fig. 10 is a view similar to Fig. 6 showing the positions occupied by the parts when the plunger-actuating eccentric has made one-half of a revolution from the position illustrated in Fig. 6. Fig. 11 is a view like Fig. 7 showing the position occupied by the outlet-port of the valve when the parts are in the position illustrated in Fig. 10. Fig. 12 is a view like Fig. 6 showing the position occupied by the parts after the plunger-actuating eccentric has made three-fourths of a revolution. Fig. 13 is a view similar to Fig. 7, showing the position occupied by the outlet-port of the valve when the parts are in the position illustrated in Fig. 12; Fig. 14 is a view like Fig. 2 of a modification of the construction represented in the last-referred to figure; and Fig. 15, a view in end elevation of the structure shown in Fig. 14 illustrating the mechanism therein provided for driving the fluid-forcing plunger.

The casing of my improved distributing means is represented at 14, this casing containing a bore 15, preferably tapered as illustrated in which a tapered rotatable distributing-member 16 is rotatably mounted, the stem of the member 16 being represented at 17 and journaled in a bearing 18 of the casing 14. The member 16 is so proportioned relative to the bore 15 that a chamber 19 will be provided between its inner end (of smaller diameter) and the adjacent end-wall of said bore, this chamber communicating with a passage 20 in said casing which opens into a pipe 21, which in practice would be connected with the supply of oil to be distributed. In the particular arrangement illustrated, provision is made for forcing oil through two pipes to the bearings or other parts to be lubricated, these pipes being represented at 22 and 23 and opening into passages 24 and 25, respec-

tively, in the casing 14, the passages 24 and 25, opening into the bore 15. The member 16 contains, in its smaller end, peripheral recesses or pockets 26, 27, 28 and 29, the recesses 26 and 28 being out of communication with each other, and the recesses 27 and 29 being in communication through the medium of a passage 30, the recesses 26 and 28 being in communication with the space 19, and consequently the pipe 21, through the medium of passages 31 and 32, respectively, which open at one end into said recesses and at their opposite ends through the reduced end of the member 16, the recesses 26, 27, 28 and 29, being equidistantly spaced about the periphery of the member 16. A passage 33 communicates at one end with the passage 30, and consequently the recesses 27 and 29, and at its other end opens into a recess or pocket 34 provided in the periphery of the member 16 at its larger end and adapted to be moved into registration, successively, with the passages 24 and 25 when the member 16 is rotated.

Coöperating with the member 16 is a plunger 35 which is guidedly confined in a bearing 36, screwed into a socket 37 in the member 14, the bottom of said socket being tapered as illustrated at 38 and communicating with a passage 39, which opens through the bore 15 at such a point as will cause the recesses 26, 27, 28 and 29 to be successively moved into registration therewith when the member 16 is rotated. The member 16 and plunger 35 coöperate with each other to cause the fluid to be pumped to be subjected to the action of the plunger for forcing it through the pipes to the parts to be lubricated, a description of the particular mechanism illustrated for accomplishing this operation being as follows: Journaled in bearings 41 in the upper end of the casing 14 is a shaft 42 carrying an eccentric 43 into contact with which the upper end of the plunger 35 is held by a spring 35^a. The shaft 42 may be driven in any suitable manner as through the medium of a suitably driven chain 44 running over a sprocket 45 on said shaft. Where the various passages and recesses of the member 16 and the casing 14 are provided as illustrated and hereinbefore described, the member 16 should rotate at one-half the speed of the eccentric 43, and to this end, I provide the gear arrangement illustrated comprising a gear 46 secured on the shaft 43 and a gear 47 on the shaft 17 meshing with the gear 46, the gear 47 being the larger of the two and the ratio between these gears being two to one.

The operation of the mechanism in so far as it has been described is as follows: Assuming the parts to be in the position illustrated in Fig. 6, wherein the plunger 35 is

depressed to the maximum extent, rotation of the shaft 42 to the right in Fig. 6 throughout a quarter revolution carries the eccentric 43 to the position illustrated in Fig. 8 and moves the recess 26 into communication with the passage 39. In this movement of the eccentric 43 the plunger 35 rises under the action of the spring 35^a, thus drawing fluid from the pipe 21 through the passage 31 into the recess 26 and into the passage 39 and the cavity above the latter. Further revolution of the shaft 42 to the right in Fig. 6 throughout another quarter revolution carries the eccentric 43 to the position illustrated in Fig. 10, wherein the plunger 35 is at the extreme end of its upper stroke. Further rotation of the shaft 42 in Fig. 6 throughout another quarter revolution carries the eccentric to the position illustrated in Fig. 12, and the recess 29 into registration with the passage 39, the movement of the eccentric 43 as described, causing the plunger to move downwardly. The downward stroke of the plunger 35 from the position illustrated in Fig. 10 to the position illustrated in Fig. 6 (the intermediate position being represented in Fig. 12), causes the fluid which is sucked into the passage 39 and the cavity above the latter, to be forced into the recesses 29 and 27 and out through the passage 33 into the recess 34, from which it escapes through the passage 24 into the pipe 22 through which it is conducted to the part to be lubricated, it being understood that the recess 34 by being disposed as illustrated and described will be moved into registration with the passages 24 and 25 successively, and that it will register with one of the passages with each downward movement of the plunger 35 as the latter makes two complete reciprocations to every revolution of the member 16. It will, therefore, be readily understood that oil will be alternately forced through the pipes 22, and 23, in substantially equal amounts. Furthermore, it will readily be understood that by re-arranging the ports, passages and recesses of the mechanism described, the oil may be forced through any desirable number of leads. Where it is desired to vary the amount of fluid pumped with each operation of the device, any suitable means for regulating the stroke of the plunger 35 may be employed. I prefer, however, to use the means illustrated and of which the following is a description: Rotatably supported on the shouldered end 48 of the bearing 41 is an eccentric 49 of substantially the same diameter as the eccentric 43, the eccentric 49 being so positioned that it will extend into the path of upward movement of the plunger 35 and thus limit the movement of the latter depending upon the position to which the eccentric 49 is adjusted on the bearing 41, it being understood that the eccentric 49 merely acts as a stop

and prevents the plunger 35 from following the eccentric 43 throughout the movement of the latter, to a greater or less extent, depending upon the adjustment of the eccentric 49.

- 5 In the particular arrangement illustrated my improved distributing means is shown in connection with an internal-combustion engine wherein, as is well understood in the art, provision should be made for supplying 10 oil to the parts to be lubricated at relatively greatly increased proportions, the faster the engine is operated. In the arrangement illustrated the eccentric 49 is shown as operatively connected with the throttle-control 15 of the engine, whereby as the throttle-opening is increased, the eccentric 49 is shifted to permit the plunger 35 to have greater upward movement. The intake-pipe of an internal-combustion engine is represented at 20 50 and contains a throttle 51 connected with the usual throttle-rod 52, and is pivoted at 53 to the controlling lever 54 usually provided on an automobile. The eccentric 49 is provided with an arm 55 pivotally connected 25 as indicated at 56 with a rod 57 which is pivotally connected as indicated at 53 with the lever 54.

It will be understood from the drawings and the foregoing description that actuation 30 of the lever 54 simultaneously operates the throttle 51 and eccentric 49 to cause the stroke of the plunger 35 to be reduced as the throttle closes and increased as the throttle opens, and thus increased flow of oil, 35 in any desired proportion, to the parts to be lubricated as the engine increases its speed, may be provided for.

Referring to the construction illustrated in Figs. 14 and 15, instead of driving the 40 fluid-forcing plunger by means driven from a shaft separate from the rotating member 16, requiring the use of gears or other means to drive these two members, in timed relation to each other, it is driven by means 45 supported on an extension of the member 16, this member being directly driven from any suitable source, instead of indirectly, as in the construction of the preceding figures. In this construction the supply-pipe opens 50 through the casing 14 into an annular channel 55 in the periphery of the member 16, and the pockets 26 and 28 communicate with the said channel through the medium of short passages 56 in the periphery of the 55 member 16, one only of said passages being shown. The small end of the member 16 carries a rod extension 57, which is equipped with diametrically opposed cams 58, the smaller end of the casing 14 being of reduced diameter, as indicated at 57^a, to form a bearing surface for an eccentric 59, which corresponds with and operates in the same manner as the eccentric 49. The plunger 35 in this construction operates in a passage 60, 60 which corresponds with the passage 39, its

inner end being in line with the recesses 26, 27, 28 and 29. The plunger 35 is held up against the outer peripheries of the cams 58, by means of a spring 61, and when the member 16, together with its rod-section 57, 70 is rotated in any suitable manner, as through the medium of a sprocket 62 secured to the stem 17 of the member 16, it will cause the plunger 35 to be given two complete reciprocations upon each complete rotation of the 75 member 16, the plunger upon each upward movement, drawing a charge of oil from the supply thereof into the recess 26 or 28, depending upon which one is in registration with the passage 60, and upon each downward stroke forcing the oil, thus drawn from the supply, into the recess 27 or 29, depending upon which one is in registration with the passage 60, and thence into the exhaust recess 34 through the passage 33, from 80 which it is forced into one or the other of the outlets 24 or 25, depending upon the position of the exhaust recess 34.

As before stated, my improved mechanism may be used for distributing fuel to the cylinders of an internal combustion engine, it being required, however, when the mechanism is so used, that the member 16 be driven in any suitable way in timed relation to the movements of the pistons in the cylinders 90 to be supplied with fuel, for causing the fuel to enter the cylinders at the proper time.

What I claim as new and desire to secure by Letters Patent is—

100

1. In a device of the character set forth, the combination of a casing containing a passage opening into its interior, a plunger reciprocable in said passage, said casing containing an inlet port and a plurality of outlet ports, a rotatable member in said casing containing in its periphery a plurality of recesses which are successively moved into and out of registration with said passage upon rotation of said member, alternate ones of said recesses registering with said inlet port, said member containing a passage registering with the others of said recesses and adapted to be moved into registration successively with said outlet ports, and means 105 for actuating said member and plunger in timed relation, for the purpose set forth.

2. In a device of the character set forth, the combination of a casing containing a passage opening into its interior, a plunger reciprocable in said passage, said casing containing an inlet port and a plurality of outlet ports, a rotatable member in said casing containing in its periphery a plurality of diametrically-opposed recesses which are 110 successively moved into and out of registration with said passage upon rotation of said member, alternate ones of said diametrically-opposed recesses registering with said inlet port, said member containing a passage reg- 115

istering with the other of said diametrically opposed recesses and adapted to be moved into registration successively with said outlet ports, and means for actuating said member and plunger in timed relation, for the purpose set forth.

3. In a device of the character set forth, the combination of a casing containing an inlet and an outlet, a plunger, cam means 10 for operating said plunger, rotary means in said casing coöperating with said plunger for discharging through said outlet fluid entering said casing through said inlet, and an adjustable eccentric device for limiting the 15 stroke of said plunger under the action of said cam.

4. In a device of the character set forth, the combination of a casing containing an inlet and a plurality of outlets, a plunger, 20 means for operating said plunger, means co-operating with said plunger for discharging successively through said outlets, fluid entering said casing through said inlet, and a single adjusting means for varying the stroke 25 of said plunger.

5. In a device of the character set forth, the combination of a casing containing an inlet and a plurality of outlets, a plunger for drawing charges into said casing, means 30 for operating said plunger, means coöperating with said plunger for discharging a charge through each outlet, in succession, and a single adjusting means for varying the stroke of said plunger.

35 6. In a device of the character set forth, the combination of a casing containing an inlet and a plurality of outlets, a plunger, means for operating said plunger, means for causing a charge of fluid to enter said casing 40 through said inlet upon each movement of said plunger in one direction and to discharge a charge through each outlet, in succession, and a single adjusting means for varying the stroke of said plunger.

45 7. In a device of the character set forth, the combination of a casing containing an inlet and a plurality of outlets, a plunger, means for operating said plunger, rotary means coöperating with said plunger for 50 causing a plurality of charges to enter said

casing, successively, in a single revolution of said rotary means and discharging said charges through said outlets, in succession, and a single adjusting means for varying the stroke of said plunger.

8. In a device of the character set forth, the combination of a casing containing an inlet and a plurality of outlets, a plunger, means for operating said plunger, a rotary member in said casing coöperating with said plunger for causing a plurality of charges to enter said casing, successively, in a single revolution of said rotary means and discharging said charges through said outlets, in succession, means for rotating said member 60 in timed relation to said plunger, and a single adjusting means for varying the stroke of said plunger.

9. In a device of the character set forth, the combination of a casing containing a 70 radially-disposed passage opening into its interior, a plunger reciprocable in said passage, said casing containing an inlet port in one end and a plurality of radially-disposed outlet ports, a rotatable member in said casing containing in its periphery a plurality of recesses which are successively moved into and out of registration with said passage upon rotation of said member, alternate ones of said recesses registering with said inlet 80 port, said member containing a passage registering with the others of said recesses and adapted to be moved into registration successively with said outlet ports, and means for actuating said member and plunger in 85 timed relation, for the purpose set forth.

10. In a device of the character set forth, the combination of a casing containing an inlet and an outlet, a plunger, a shaft, a cam secured to said shaft, an eccentric journaled 90 on said shaft, means for operating said shaft, means for adjusting said eccentric, and means coöperating with said plunger for discharging through said outlet fluid entering said casing through said inlet.
